S. W. BRADBURN

SILENCING DEVICE FOR VALVE MECHANISM

Filed May 2, 1921

FIG. 1

FIG. 1

FIG. 2

FIG. 3

INVENTOR
Stanley W. Bradburn,
34 Charles Avenue,
New Haven,
Conn.

UNITED STATES PATENT OFFICE.

STANLEY W. BRADBURN, OF HAMMOND, INDIANA.

SILENCING DEVICE FOR VALVE MECHANISM.

Application filed May 2, 1921. Serial No. 466,356.

To all whom it may concern:

Be it known that I, STANLEY W. BRADBURN, a citizen of the United States, and a resident of Hammond, Lake County, and 5 State of Indiana, have invented certain new and useful Improvements in Silencing Devices for Valve Mechanism, of which the following is declared to be a full, clear, and exact description.

10 This invention relates to silencing device for poppet valves of internal combustion engines, and its principal object is to eliminate the noise which is usually occasioned by the ordinary valve actuating mechanism of internal combustion engines. It is well understood by those skilled in this art, that a slight amount of lost motion is provided in some portion of the valve actuating mechanism for the purpose of enabling the valve 15 to seat under the influence of its spring, and the noise or clicking sound is occasioned by the coming into contact of the two surfaces that are spaced apart to obtain the lost motion. I have overcome this objectionable 20 feature by providing a device which allows of lost motion in the valve actuating mechanism, but which has no spaced surface that come into contact, but, on the contrary, all 25 of the contacting surfaces constantly remain in contact. Another object is to provide a silencing device which positively eliminates the clicking sound, which may be employed in the form of valve mechanism commonly known as the "overhead type." 30

35 Another object is to provide a silencing device of simple, practical and substantial construction, wherein the parts are not liable to become rapidly worn or damaged.

With these and other objects and advantages in view, this invention consists in a silencing device for poppet valves of internal combustion engines, comprising a two part member for transferring motion from one reciprocating member to another, and 45 having lost motion between its two parts, wherein contacting surfaces are constantly kept in contact with each other. The invention further consists in a silencing device of the character above set forth, in which a third 50 or compensating member is employed for connecting together the two parts of the two part member, said third member having a continuous surface contact with said two

parts, but permitting of lost motion therebetween. The invention further consists in the 55 several novel features hereinafter fully set forth and claimed.

The invention is clearly illustrated in the drawing accompanying this specification in 60 which:—

Fig. 1 is a side elevation of a silencing device embodying one form of the present invention; Fig. 2 is a side elevation (partly broken out) but showing the parts in a different position; Fig. 3 is a vertical, cross-section taken on the line 3—3 of Fig. 2; Fig. 4 is a plan of a slightly modified form of the invention; Fig. 5 is a side elevation of said modified form; Fig. 6 is a view partly in side elevation and partly in central, vertical, longitudinal section of said modified form; and Fig. 7 is a view similar to Fig. 6 but showing the parts in a different position.

Referring to said drawing and first to 75 Figs. 1 to 3, inclusive, the reference character 10 designates a primary actuating member, such as a push rod, and 11 designates the valve stem of valve mechanism of the "overhead type" for internal combustion engines. As is well understood, the push rod 10 is reciprocated by a cam (not shown) to unseat the valve and a valve spring (not shown) is employed around the valve stem 10 to seat the valve when permitted to do so by the cam and interposed mechanism. In the ordinary practice, a rocker arm is provided between the push rod and valve stem for transferring motion from the push rod to the valve stem to unseat the valve and for transferring motion 80 from the valve stem to the push rod when the valve spring acts to seat the valve. It is also well understood that in common practice, clearance is left between the rocker 85 arm and valve stem to permit the valve to seat under the influence of the spring, when the low side of the cam engages with the push rod.

In accordance with one form of my invention, a rocker arm 12 is employed between the push rod and valve stem, which rocker arm 12 is composed of two parts, 13, 14, having a limited amount of lost motion between them, and an interposed compensating member 19 which permits of the lost motion each 100

time that the rocker arm is actuated, but maintains a constant contact between the bearing surfaces, thus eliminating the usual gap which must be closed to make contact 5 between the parts.

As illustrated, in the preferred form the rocker arm comprises a rocker arm member 13, which is connected to the push rod 10, and a rocker arm member 14, which has one 10 end 15 that engages with the end of the valve stem and is held in constant contact therewith. The rocker arm is rotatably mounted on a shaft or stud 16, which is mounted on the engine in any suitable manner. One arm 17 of the rocker arm member 14 is connected to the rocker member 13, so as to move therewith, and, as shown, said arm 17 may be forked at 18 to straddle the rocker arm member 13, and the two are 15 connected together by the interposed compensating member 19, which is capable of rocking or rotating with respect to both rocker arm members 13, 14, and is so connected to said rocker arm members 13 and 20 14 as to permit of a limited amount of lost motion between the two, each time the rocker arm is actuated by the push rod 10 or valve stem 11, without, however, permitting any of the bearing surfaces to be 25 come separated, but on the other hand keeping said surfaces in constant contact. Said compensating member 19 may be in the form of a crank or an eccentric, cam, or the like, and in the preferred form, it is illustrated as comprising a connecting pin rotatively mounted in the rocker arm member 13, and having two eccentrically disposed end portions 20, rotatively mounted in the forks 18 of the rocker arm member 14. For 30 convenience in removing the parts, the bearing apertures in the forks are made large enough to permit the pin to be inserted through them, and sleeves 21 are placed in the bearing apertures in the forks and 35 around the eccentric portions 20. I have illustrated cotter pins 22 secured in the eccentric portions 20 of the pin 19 for holding it in place, although it is to be observed that many equivalent arrangements may be 40 substituted to hold the eccentric pin or crank position between the rocker arm members 13, 14. Between said rocker arm members 13, 14, is interposed a spring 23 which is here shown in the form of a coiled compression spring seated in recesses 24, 25, formed in the opposing sides of the rocker arm members 13, 14. Said spring is located 45 and arranged between the eccentric pin 19 and stud or shaft 16, and tends constantly 50 but yieldingly to hold the push rod in constant contact with the cam.

Because of the eccentric connection between the rocker arm members 13, 14, a limited amount of lost motion is permitted 55 between said two rocker arm members, thus

enabling the valve to seat perfectly, but at all times during the operation of the mechanism are all contacting surfaces kept in close contact. Fig. 1 shows the parts in position assumed when the valve is seated and the 60 low part of the cam has come into engagement with the push rod 10. In this position, the axes of the two parts of the eccentric pin 19 are substantially in a line running through the axis of the support for 65 the rocker arm. When the high part of the cam first engages the push rod and commences to lift it, the initial upward movement of the push rod carries the eccentric pin up, causing it to travel in an arc of a 70 circle around the axis of the eccentric portions 20, which are in the forks of the rocker arm member 14. When the axes of the eccentric pin come into vertical alignment (see Fig. 2), the eccentric portions 20 commence 75 their lifting action on the forks of the rocker arm member 14, thereby depressing the end 15, and consequently depressing the valve stem 11 and unseating the valve. After the high side of the cam has passed the push 80 rod, and the latter starts down toward the low side of the cam, the valve spring lifts the valve stem, swings the end 15 of the rocker arm member 14 upward and swings the forked end 18 downward, and when 85 the valve has been seated and the upward movement of the rocker arm member end 15 ceases, the rocker arm member 13 continues to move downward under the influence of the spring 23, until such movement is arrested by the coming into engagement of the push rod with the low side of 90 the cam. It is to be observed that the amount of lost motion may be and should be limited to permit the eccentric pin to 95 turn less than one hundred and eighty degrees before the push rod reaches its lowermost position.

It will be observed therefore, that, although the push rod and valve stem may 100 move slightly with relation to each other, and thereby move one of the rocker members with respect to the other, the connections are always kept in contact, so that at no time is there any gap between any of the contacting surfaces. It is understood that in the operation of an internal combustion engine of the type employed in automobiles or other motor vehicles or aeroplanes, the reciprocations of the push rod and valve stem are 105 extremely rapid and in quick succession, and that the lost motion is taken up each time the parts are reciprocated.

In the form illustrated in Figs. 4 to 7, inclusive, the two rocker arm members 13^a, 14^a, 110 of the rocker arm are pivotally connected together, and for convenience are pivotally mounted upon the shaft or stud 16^a. Springs 115 26 are employed to swing or spread the two members 13^a, 14^a apart. The push rod 10^a 120

is connected to the rocker arm member 13^a and the end 15^a of the rocker arm member 14^a engage the valve stem 11^a, as in the preferred form. In this case, both of the rocker 5 arm members 13^a and 14^a have a limited amount of rocking movement upon their support, to obtain the necessary lost motion between the push rod 10^a and valve stem 11^a. In this form of the invention, two rocking 10 cam members 19^a are employed, which cam members are contained in recesses in the members 13^a, 14^a, and are mounted upon pins or studs 20^a that are secured in said rocker arm members. Said rocking cam members 15 have curved surfaces 20^b which are eccentrically disposed with respect to the axes of the pins 20^a and said curved surfaces of the rocking cam members 19^a are constantly held in contact by springs 23^a which are located, in sockets formed in the opposite faces of the rocking members 13^a, 14^a. It 20 is to be observed that when force is applied to either end of the rocker arm in an upward direction, the rocking cam members 19^a will roll against each other upon their eccentric surfaces, until the minor axes of said eccentric surfaces lie in a straight line, which 25 position of the rocking cam members is illustrated in Fig. 6. When, however, the upward force is relieved on either end of the 30 rocker arm, the springs 26 then act to spread the two rocker arm members 13^a, 14^a apart, while the springs 23^a act to keep the eccentric faces of the rocking cam members 19^a 35 in rolling contact, as is clearly indicated in Fig. 7. It will thus be seen that, although the two rocker arm members 13^a, 14^a, of the rocker arm are free to rock independently of each other so as to maintain constant contact with the push rod and valve stem, the compensating element, namely the rocking cams, remain in constant contact, so that when the rocker arm members are brought back to their initial position, all of the 40 contacting surfaces remain in contact, thereby eliminating any clicking sound which would otherwise occur in case any of the surfaces became separated from each other.

More or less variation of the exact details 50 of construction is possible without departing from the spirit of this invention; I desire, therefore, not to limit myself to the exact form of the construction shown and described, but intend, in the following claims, 55 to point out all of the invention disclosed herein.

I claim as new and desire to secure by Letters Patent:

1. A silencing device for poppet valves, 60 comprising a primary actuating member, a valve actuating member actuated by said primary actuating member, and bodily connected thereto and having a limited amount of lost motion with respect thereto, and a 65 rotative, compensating element, mounted in

one of said members and having a non-concentric bearing face continuously contacting in the other.

2. A silencing device for poppet valves, 70 comprising a primary actuating member, a valve actuating member actuated by said primary actuating member, and having a limited amount of lost motion with respect thereto, and a rotative, compensating element held in continuous contact in both of 75 said members.

3. A silencing device for poppet valves, 80 comprising a primary actuating member, a valve actuating member actuated by said primary actuating member, and having a limited amount of lost motion with respect thereto, and a rotative, eccentric member having non-concentric bearing surfaces, one having its bearing in one of said members and one having its bearing in the other of 85 said members.

4. A silencing device for poppet valves, 90 comprising a primary actuating member, a valve actuating member actuated by said primary actuating member, and having a limited amount of lost motion with respect thereto, and a connecting pin, rotatively mounted in one of said members and having an eccentric portion rotatively mounted in the other of 95 said members.

5. A silencing device for poppet valves, 100 comprising a push rod, a valve stem, and a rocker arm member for transferring movement from one to the other, said rocker arm having an eccentric connection with said push rod whereby a limited amount of lost motion is had between said push rod and rocker arm member.

6. A silencing device for poppet valves, 105 comprising a push rod, a valve stem, a rocker arm member for transferring movement from one to the other and a compensating connecting element positively connected to said rocker arm and push rod which admits of a limited amount of lost motion between 110 said push rod and rocker arm member.

7. A silencing device for poppet valves, 115 comprising a push rod, a valve stem, a rocker arm member, for transferring movement from one to the other, and an eccentric pin connection between said push rod and rocker arm member.

8. A silencing device for poppet valves, 120 comprising a primary actuating member, a valve actuating member actuated by said primary actuating member, and having a limited amount of lost motion with respect thereto, and a rotative, spring pressed, compensating element, rotatably mounted in one of said members and having a non-concentric bearing face rotatably mounted in the other member.

9. A silencing device for poppet valves, 125 comprising a primary actuating member, a valve actuating member actuated by said

primary actuating member, and having a limited amount of lost motion with respect thereto, and a rotative, spring pressed, compensating element rotatably secured in both 5 of said members.

10. A silencing device for poppet valves, comprising a primary actuating member, a valve actuating member actuated by said primary actuating member, and having a limited amount of lost motion with respect thereto, and a rotative, spring pressed, eccentric member having non-concentric bearing surfaces, one surface bearing in one of said members and the other surface bearing 15 in the other of said members, whereby said primary actuating member and valve actuating member are positively connected together.

11. A silencing device for poppet valves, 20 comprising a primary actuating member, a valve actuating member actuated by said primary actuating member, and having a limited amount of lost motion with respect thereto, and a spring pressed connecting pin, 25 rotatively mounted in one of said members and having an eccentric portion rotatively mounted in the other of said members, whereby said primary actuating member

and valve actuating member are positively connected together. 30

12. A silencing device for poppet valves, comprising a push rod, a valve stem, and a rocker arm member for transferring movement from one to the other said rocker arm having a spring pressed eccentric lost motion connection positively connected with said push rod whereby a limited amount of lost motion is had between said push rod and rocker arm member. 35

13. A silencing device for poppet valves, 40 comprising a push rod, a valve stem, a rocker arm member for transferring movement from one to the other and a spring pressed compensating connecting element between said rocker arm and push rod which 45 admits of a limited amount of lost motion between said push rod and rocker arm member.

14. A silencing device for poppet valves, comprising a push rod, a valve stem, a 50 rocker arm member, for transferring movement from one to the other, and a spring pressed eccentric pin lost motion connection between said push rod and rocker arm member.

STANLEY W. BRADBURN.
